UNITED STATES PATENT OFFICE.

JAS F. MONROE, OF FITCHBURG, MASSACHUSETTS.

LUBRICATOR.

Specification of Letters Patent No. 16,018, dated November 4, 1856.

To all whom it may concern:

Be it known that I, JAS. F. MONROE, of Fitchburg, in the county of Worcester and State of Massachusetts, have invented certain new and useful Improvements in Lubricating-Cups for Oiling Steam Machinery, of which the following is a full, clear, and exact description, reference being had to the accompanying drawings, making part 10 of this specification, in which—

Figure 1 is a plan; Fig. 2, a vertical section upon the line A A of Fig. 1; Fig. 3, a horizontal section upon the line B B of Fig. 2; Fig. 4, a horizontal section upon the line 15 C C of Fig. 2.

It has long been a desideratum to make use of tallow for the purpose of lubricating the cylinders of steam engines, but no suitable method has been known of keeping the 20 tallow constantly in a molten state and ready for use.

My invention has for its object to enable me to employ this substance for the purpose, and consists in surrounding the lubricating 25 cup with a steam chamber whereby the lubricating material is always preserved in a liquid state ready for use as will be hereafter more fully explained, and my invention also consists in so arranging the parts 30 through which the lubricating material is delivered to the cylinder that the pressure of the steam within the cylinders shall always tend to close them, whereby the joints are kept tight and leakage of steam is avoided.

To enable others skilled in the art to understand my invention, I will proceed to describe the manner in which I have carried it out.

In the accompanying drawings D is the 40 lubricating cup, the bottom of which forms the upper seat of the plug or valve E, and is perforated for the passage of the stem F, of the valve. Through the bottom of the lubricating cup there are two holes corresponding to the two holes a, and b, in the 45 top of the plug. One of these holes in the cup is left open for the passage of the tallow, and into the other is fitted the tube or pipe G, the object of which will be presently 50 explained. The plug E, is of the form represented in section in Fig. 2, and fits closely upon its seat on the bottom of the lubricating cup. Its interior dimensions are such as to enable it to contain the amount of lubri-

cating material which at any one time may 55 be required within the cylinder. Beneath the plug is fitted with a tight joint the plate H which is prevented from turning by the pins f, that enter the straps I when the cup is not in use. This plate H, is held up 60 against the plug E, and the latter up against its seat upon the bottom of the cup by the spring K. When in operation the parts are all held in place by the pressure of the steam which tends constantly to keep the joints 65 tight and prevent leakage of steam. Through the bottom of the plug is the hole h, which corresponds in a certain position of the plug to the hole i in the plate H. The plug E is revolved by means of the handle 70 L, attached to its shaft.

The whole of the apparatus thus described is surrounded by the casing M, between which and the lubricating cup there is a space, which is brought into communication 75 with the steam in the cylinder, and thus the cup is kept constantly heated and the lubricating material which it contains is constantly maintained in a liquid state. I am thus enabled to employ tallow for the purpose of lubricating the cylinder, a material 80 peculiarly adapted to the purpose and costing much less than the oils heretofore employed for the purpose.

Operation: When the plug E, is turned in 85 a certain position, one of the holes through the bottom of the lubricating cup falls over the hole b, in the plug and the molten tallow or other lubricating material flows into the plug, any steam or air which may remain 90 in the latter passing off through the tube G. When the plug is again turned, the holes a, and b, are closed and the communication is 95 cut off between the plug and either the lubricating cup or the external air. In another position of the plug its hole h, is made to correspond with the hole i, in the plate H, and the liquid within the plug passes down to the cylinder. When in use the plug is turned so as to open the passage from the 100 lubricating cup to the plug. When in this position the holes h, and i, are also closed and the steam from the cylinder is prevented from entering the plug. When the plug is turned so as to permit the tallow to flow out 105 of the plug into the cylinder the holes a, and b, are closed and the steam in the plug is prevented from blowing out.

In lieu of surrounding the lubricating cup by a steam chamber, as above described, it may be surrounded by a coil of pipe filled with steam and the same end will be gained.

5 What I claim as my invention and desire to secure by Letters Patent is—
The plate H and plug E as arranged and

combined with each other and with the lubricating cup for the purpose set forth.

JAMES F. MONROE.
